UNITED STATES PATENT OFFICE

BATTISTA GIOVANNI GILLIO, OF WORCESTER, MASSACHUSETTS

ELECTRICITY GENERATING APPARATUS

Application filed January 11, 1932. Serial No. 536,004.

The present invention relates to an electricity generating apparatus and has for its primary object to provide, in a manner as hereinafter set forth, an apparatus of this character embodying a novel construction, combination and arrangement of parts through the medium of which wind is utilized for actuating one or more generators.

Other objects of the invention are to provide an electricity generating apparatus of the aforementioned character which will be simple in construction, strong, efficient and reliable in use and which may be manufactured at low cost.

15 All of the foregoing and still further objects and advantages of the invention will become apparent from a study of the following specification, taken in connection with the accompanying drawings wherein like characters of reference designate corresponding parts throughout the several views, and wherein:—

Figure 1 is a view in top plan of an apparatus in accordance with the present invention.

Figure 2 is a view in vertical longitudinal section through the apparatus.

Figure 3 is a view in elevation looking at the intake end of the conduits.

30 Figure 4 is a view in vertical cross section through the conduits showing the means for supporting the same on the frame.

Figure 5 is a detail view in front elevation of one of the conduit supporting brackets.

35 In the embodiment of the invention illustrated in the drawings, the reference numeral 1 designates generally a frame comprising the longitudinal side bars 2 between the ends of which the front and intermediate cross bars 3 and 4, respectively, extend. The cross bar 3 extends beyond the side bars 2 and terminates in depending arms 5 upon which the front supporting wheels 6 are mounted for rotation.

40 The frame 1 further includes the longitudinal bars 7 which are inwardly offset with respect to the bars 2 and connected, at their forward ends, to the cross bar 4. A cross bar 8 extends between and beyond the bars 7 at the rear ends thereof, said bar 8 being

coextensive with the bar 3 and terminating, at its ends, in the depending arms 9 upon which the rear supporting wheels 10 are mounted for rotation.

45 A transverse shaft 11 is journaled in bearings provided therefor on the lower sides of intermediate portions of the bars 7 of the frame 1, said shaft 11 projecting laterally beyond the bars 7 and being operatively connected, at its ends, to the generators 12 which are mounted on suitable supporting brackets 13 which extend from the bars 7. A wind wheel 14 is fixed on the shaft 11 between the bars 7.

50 The reference numeral 15 designates a series of wind conduits which are mounted substantially longitudinally beneath the frame 1. The conduits 15 taper from their front ends to their rear ends and have said rear ends positioned adjacent the wind wheel 14 in a manner to cause the rapid rotation of said wind wheel by air directed against the blades thereof by the conduits when the apparatus is moved forwardly or when sufficient air is passed through the conduits. This is illustrated to advantage in Figure 2 of the drawings. At the forward or intake ends thereof the conduits 15 are provided with a common flared mouth 16 for directing the wind thereinto.

55 A hanger 17 depends from the bar 4 of the frame 1 and the rear ends of the conduits 15 are supported on said hanger 17 by a bracket 18 of a construction illustrated to advantage in Figures 4 and 5 of the drawings. The forward ends of the conduits 15 are supported on the cross bar 3 of the frame 1 by a bracket 19 which is similar to the bracket 18 with the exception that it is larger to accommodate the comparatively large forward end portions of the conduits.

60 In use, the apparatus may be connected to the front of a suitable vehicle, such as an automobile or railroad car to be driven forwardly thereby. Forward movement of the apparatus causes air to pass through the flared mouth 16 into the conduits 15 from which said air is discharged under considerable pressure through the comparatively small or restricted rear ends of the conduits 100

against the blades of the wheel 14. The wheel 14 is, of course, rotated by the pressure of the air thereagainst and the generators 12 are actuated. The electric current from the generators 12 may be used for any desired purposes, as for charging storage batteries on the vehicles. The storage batteries may, of course, be used for any purpose, as for lighting, ignition or for the starting motor 10 of the vehicle if said vehicle is an automobile. If sufficient wind is blowing the apparatus may remain stationary and still function satisfactorily if disposed with its forward end toward the wind. Also, if desired, the wheeled supporting frame may be dispensed with and the apparatus mounted on the body of the vehicle.

It is believed that the many advantages of an electricity generating apparatus in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

In combination with a vehicle including a frame, a transverse shaft journalled in the rear part of the frame, an elongated wind wheel carried by the shaft, a transversely arranged hanger depending from the frame in front of the wind wheel, a substantially channel-shaped bracket depending from the hanger and having its bight part formed with a number of substantially semi-circular recesses, a similar bracket depending from the forward part of the frame, a substantially horizontal row of rearwardly tapered tubes, each of which has its rear part fitting in a recess of the rear bracket and a forward part fitting in a recess of the front bracket, the rear ends of the tubes directing air passing therethrough against the wind wheel and the front ends extending in front of the frame, and a horizontally arranged elongated flaring mouth forming member having a horizontal row of openings in its rear and small end for receiving the front ends of the tubes, the length of the rear end of the row of tubes being slightly greater than the length of the wind wheel.

In testimony whereof I affix my signature.

BATTISTA GIOVANNI GILLIO.
